US0D1087981S

(12) **United States Design Patent** (10) **Patent No.:** **US D1,087,981 S**
Chen et al. (45) **Date of Patent:** **** Aug. 12, 2025**

(54) **DISPLAY SCREEN WITH GRAPHICAL USER INTERFACE**

(71) Applicant: **ResMed Corp.**, San Diego, CA (US)

(72) Inventors: **Cindy Ann Chen**, San Diego, CA (US);
Rafael J. Rodriguez, Chula Vista, CA (US)

(73) Assignee: **ResMed Corp.**, San Diego, CA (US)

(**) Term: **15 Years**

(21) Appl. No.: **29/858,432**

(22) Filed: **Oct. 31, 2022**

(51) **LOC (15) Cl.** **14-04**

(52) **U.S. Cl.**

USPC **D14/485**

(57) **CLAIM**

The ornamental design for a display screen with graphical user interface as shown and described.

DESCRIPTION

The SOLE FIGURE is a front view of a display screen with graphical user interface showing our new design.

The outermost broken lines illustrate an electronic device and form no part of the claimed design. The remaining broken lines showing a display screen and the graphical user interface form no part of the claimed design.

1 Claim, 1 Drawing Sheet
